(57) **CLAIM**

The ornamental design for an orthodontic molar appliance, as shown and described.

DESCRIPTION

FIG. 1 is a perspective view of an orthodontic molar appliance showing the new design;

FIG. 2 is a top view thereof;

FIG. 3 is a bottom view thereof;

FIG. 4 is a left side view thereof;

FIG. 5 is a front end view thereof;

FIG. 6 is a rear end view thereof; and,

FIG. 7 is a right side view thereof.

It is understood that the surface shading is not intended to be indicative of gloss or texture. The broken lines shown in the figures represent portions of the orthodontic molar appliance that form no part of the claimed design.
